UNITED STATES PATENT OFFICE.

ALEXANDER E. BLOCK, OF ST. LOUIS, MISSOURI.

COMBINED HEEL AND ARCH SUPPORT.

1,191,655.

Specification of Letters Patent. Patented July 18, 1916.

Application filed November 25, 1914. Serial No. 873,911.

To all whom it may concern:

Be it known that I, ALEXANDER E. BLOCK, a citizen of the United States, and a resident of St. Louis, Missouri, have invented 5 certain new and useful Improvements in Combined Heel and Arch Supports, of which the following is a specification.

My invention relates to a combined heel- and arch-support, and has for its object to 10 provide an adjustable support for the treatment of the human foot in cases where both the heel and the arch are in abnormal condition, as the result of mal-formation, accident or disease, and is intended for insertion and use in a boot or shoe of ordinary construction.

In the drawings Figure 1 is an inverted plan view of a structure embodying my invention, showing a portion of the flap 7 20 broken away. Fig. 2 is a perspective view of the flap-covered portion of said structure. Fig. 3 is a transverse sectional view of the structure, not inverted, taken on the line 3—3 of Fig. 1. Fig. 4 is a longitudinal view of the device in section, taken on the line 4—4 of Fig. 1.

As shown in the drawings, I employ an insole 4, beneath which flaps 5, 6 and 7 are secured as shown in Fig. 3, said flaps being 30 secured to the lower face of the insole 4, and flaps 6 and 7 being superimposed upon each other and secured along their inner edges to each other and to the flap 5, their inner edges being in the form of an irregular curve (see Fig. 1) and extending from a point on the heel of the insole 4 at or near the median line of the insole, to a point at the side of the insole 4 which is in front of the location of the longitudinal arch of the 40 foot of the wearer, and to the rear of the line of the transverse arch of the foot of the wearer. The device of my present invention is not intended for the treatment of the transverse arch, and it should be understood, therefore, that the word "arch" 45

as used throughout this description refers to the longitudinal arch of the human foot.

The space between the flaps 5 and 6 constitutes a cavity for the reception of the irregularly-curved insert 10, and the space 50 between the flaps 6 and 7 forms a like cavity of somewhat greater length (see Figs. 2 and 4) for the reception of the similar insert 11. The inserts 10 and 11 may be used singly or together; they are illustrated in Figs. 3 and 4 as in use simultaneously.

The flap 5 is shown as a matter of convenience in manufacture; it may be omitted, and the flaps 6 and 7 secured directly to the insole 4 without departing from my invention.

Having thus described my invention, what I claim as new and desire to have secured to me by the grant of Letters Patent is

1. In a heel- and arch-support an insole, a flap secured to the lower face of the insole and forming a pocket extending from a point on the rear edge of the insole at or near the median line thereof to a point at 70 the side of the insole beneath the longitudinal arch of the wearer, and an insert arranged to fill said pocket.

2. In a heel- and arch-support, an insole; a plurality of flaps of various lengths secured to the lower face of the insole and to each other to form cavities of various lengths, each cavity extending from a point at the rear edge of the insole near the median line of said insole and extending to a point beneath the longitudinal arch of the 80 foot of the wearer; and an insert arranged to be seated in each of said cavities.

In testimony whereof, I have signed my name to this specification, in presence of two 85 subscribing witnesses.

ALEXANDER E. BLOCK.
